United States Patent Office.

JOHN BRIGHTBILL, OF LEBANON, PENNSYLVANIA.

Letters Patent No. 91,710, dated June 22, 1869.

IMPROVEMENT IN GRAIN-SEPARATORS.

The Schedule referred to in these Letters Patent and making part of the same.

To all whom it may concern:

Be it known that I, JOHN BRIGHTBILL, of Lebanon, in the county of Lebanon, and in the State of Pennsylvania, have invented certain new and useful Improvements in Grain-Separators; and do hereby declare that the following is a full, clear, and exact description thereof, reference being had to the accompanying drawings, and to the letters of reference marked thereon.

The nature of my invention consists in the construction and general arrangement of a grain-separator, attached to a threshing-machine, whereby grain may be threshed and entirely separated from all dust, &c., more thoroughly and easier than by any other machines now in use.

In order to enable others skilled in the art to which my invention appertains, to make and use the same, I will now proceed to describe its construction and operation, referring to the annexed drawings, which form a part of this specification, and in which—

Figure 1 is a plan view, and

Figure 2, a sectional side elevation.

A A represent the frame of the machine, in the rear part of which is an inclined board, B, on which the grain is placed.

At a suitable point on the inclined board B, is a curve, on which is placed a series of rows of pins, or teeth, a a.

Above these pins is placed a roller, C, on a shaft, D, said shaft having its bearings in the sides of the frame A.

The roller C is also provided with rows of pins, or teeth e e, which work in among the pins a a, separating the grain from the straw, and carrying it down the inclined board B, then up the inclined perforated screen E.

The straw, after being carried under and in front of the roller C, passes under a series of hinged arms, F F, which rise up to allow the straw to pass, but immediately fall down again, preventing it from returning.

The rakes G G then take the straw, carrying it up the inclined screen E, and letting it fall down at the front end of the machine.

The rakes G G consist of bars placed lengthways in the machine, with teeth on their under side, and arranged on two crank-shafts H H, which have their bearings in the sides of the frame A.

These shafts are, at their ends, outside of the frame, provided with pulleys I I, one of which is connected by a band, J, with a pulley on the main shaft D.

The pulleys I I, on the other side of the machine, being connected by a pitman, K, it will be seen that the regular raking-motion is obtained for the rakes G G.

While the straw is being thus carried off, the grain falls through the holes in the perforated screen E, on to the inclined board L, which is, by side-pieces, attached to said screen, forming, as it were, a box, open at one end.

This box is suspended, in proper position, in the frame A, by means of bars M M, pivoted to the frame and the box, enabling the said box to move backward and forward. The means for producing this motion will be hereinafter set forth.

When the grain has fallen down on the board L, it drops through the opening b, on to a board, N, which is provided with a series of pins, i i, at its front end, thence on to the screen O.

The dust, cheat, &c., go through the said screen, and pass out at one side of the machine, through the spout P. The grain goes over the screen, and out on the other side of the machine, through the spout R.

The board N, screen O, and spouts P and R, are suitably arranged in one box, with open front and back.

In rear of the screen O, is a drum, S, in which the fan T is placed.

This fan is mounted on the shaft V, which has its bearings in the sides of the frame A, and is at one end provided with a pulley, w.

A belt, x, connects this pulley with a pulley on the main shaft D, and thus motion is communicated to the fan.

The other end of the shaft V is crank-shaped, and provided with two pitman-rods.

One of these, Y, connects with a lever, Z, which is pivoted to the opposite side of the frame A, and also to the under side of the board L, whereby the backward and forward motion of said board, and of the inclined perforated board or screen E is obtained.

The other pitman, f, connects with a bent lever, g, pivoted to the side of the frame A, and this lever, by means of a rod, h, to the box containing the spouts P and R, whereby a reciprocating motion is given to said box.

The main shaft D is turned by means of a crank, or by any other suitable means.

The cylinder O is covered by a box-lid, m, and the whole or a part of the machine, where the rakes are situated, is also covered with a lid, n, as shown in fig. 2.

Having thus fully described my invention,

What I claim as new, and desire to secure by Letters Patent, is—

The combination, in one machine, of the toothed cylinder C, rakes G G, board or screen E, fan T, board N, and screen O, all constructed, connected, and operating in the manner and for the purposes herein set forth.

In testimony that I claim the foregoing, I have hereunto set my hand and seal, this 5th day of October, 1868.

JOHN BRIGHTBILL. [L. S.]
